Primary Examiner — Lauren D McVey

(57) **CLAIM**

The ornamental design for a teleprompter, as shown and described.

DESCRIPTION

FIG. 1 is a perspective view of a teleprompter showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the teleprompter with the cover omitted from the main bud in order to show aspects of the design not otherwise apparent; and,

FIG. 10 is a front elevation view of the teleprompter in a detached state with the remaining structures omitted in order to show aspects of the design not otherwise apparent.

1 Claim, 10 Drawing Sheets
